Primary Examiner — Natasha Vujcic(74) *Attorney, Agent, or Firm* — Pearne & Gordon LLP(57) **CLAIM**

The ornamental design for a luminaire, as shown and described.

DESCRIPTION

FIG. 1 is a top perspective view of a luminaire;
 FIG. 2 is a top view thereof;
 FIG. 3 is a cross sectional view taken from the cut line 3-3 in FIG. 2 thereof; and,
 FIG. 4 is a cross sectional view taken from the cut line 4-4 in FIG. 2 thereof.
 The broken lines in the drawings illustrate portions of the luminaire which forms no part of the claimed design.

1 Claim, 3 Drawing Sheets(56)
